US00D764248S

(12) **United States Design Patent**
Eisinger et al.

(10) **Patent No.:** **US D764,248 S**
(45) **Date of Patent:** **** Aug. 23, 2016**

(54) **RIGHT ANGLE DRIVE**

(71) Applicants: **Darren P. Eisinger**, Carpentersville, IL (US); **Geoffrey Neubauer**, Lake in the Hills, IL (US)

(72) Inventors: **Darren P. Eisinger**, Carpentersville, IL (US); **Geoffrey Neubauer**, Lake in the Hills, IL (US)

(73) Assignee: **Nomis LLC**, Palatine, IL (US)

(**) Term: **14 Years**

(21) Appl. No.: **29/524,628**

(22) Filed: **Apr. 22, 2015**

(51) LOC (10) Cl. **08-03**

(52) U.S. Cl.

USPC **D8/70**

(58) **Field of Classification Search**

USPC D8/61, 62, 66-70; D4/102; D32/15, 17, D32/19; 173/170; 200/50.32; 310/50; 451/344, 351, 353-359, 451, 456

CPC B23B 45/003; B23B 45/008; B25F 3/00

(57) **CLAIM**

We claim the ornamental design for the right angle drive, as shown and described.

DESCRIPTION

FIG. 1 is a perspective view of the right angle drive;
FIG. 2 is a back view of the right angle drive;
FIG. 3 is a front view of the right angle drive;
FIG. 4 is a side view of the right angle drive;
FIG. 5 is a side view of the right angle drive showing the side opposite that shown in FIG. 4;
FIG. 6 is a top view of the right angle drive; and,
FIG. 7 is a bottom view of the right angle drive.
The even broken lines in the drawings illustrate portions of the right angle drive that forms no part of the claimed design.
The dash-dot broken lines illustrate boundaries of the claimed design and form no part thereof.

1 Claim, 4 Drawing Sheets
